ATTORNEY

UNITED STATES PATENT OFFICE.

ARTHUR BELL, OF NYACK, NEW YORK.

ADJUSTABLE CRUTCH.

1,270,102.

Specification of Letters Patent. Patented June 18, 1918.

Application filed February 14, 1918. Serial No. 217,144.

To all whom it may concern:

Be it known that I, ARTHUR BELL, a citizen of the United States, residing at Nyack, in the county of Rockland and State 5 of New York, have invented certain new and useful Improvements in Adjustable Crutches, of which the following is a specification.

This invention relates to certain new and useful improvements in crutches; and as its 10 primary object contemplates the provision of a crutch which may be adjusted lengthwise to adapt the same for use by persons of different heights and is constructed with such care and attention as regards the number, proportion and arrangement of parts 15 as to enable the same to be easily and cheaply manufactured and placed on the market at a reasonable cost.

Other objects and advantages of the invention will be more readily understood from the following description and drawings wherein I have illustrated the invention in its preferred embodiment and in which drawings:—

25 Figure 1 is a side elevation partly broken away of my improved crutch, and

Fig. 2 is a sectional view taken on the line 2—2 of Fig. 1.

From the drawings it will be seen that the 30 improved crutch includes a pair of complementary sections slidably secured together. The lower section comprises the legs 4 which are substantially parallel for a portion of their length and then have their lower ends 35 gradually converging toward one another, the extremities of said lower ends finally contacting with one another and being received in a socket 5. These legs 4 are connected in spaced relation by means of a short 40 transverse connecting bar 6 which is positioned a substantial distance below the upper end of the legs and at a point just above the inwardly converging portions thereof.

The upper section comprises a shoulder 45 rest 7 which is constructed in the usual manner and is adapted to have its opposite ends resting upon the upper ends of the legs 4 when the sections are arranged as in Fig. 1. Depending from this shoulder rest and disposed inwardly of its end are a pair of parallel legs 8 which as shown are received

between the legs 4 and have their lower ends supported upon the transverse bar 6. When the parts are assembled as shown in Fig. 1 it will be evident that the crutch is exceedingly strong and compact owing to the manner of connecting the sections together. The ends of the shoulder rest 7 are firmly supported upon the upper ends of the legs 4 while the legs 8 depending from the shoulder rest engage the legs 4 to prevent lateral movement and have their lower ends supported by the bars 6. Adjacent their lower ends the legs 8 are connected by a short transverse bar 9 which is adapted to provide 65 a hand grip for the user.

These legs 4 and 8 are provided with vertically spaced openings extending horizontally therethrough and adapted to be alined at times to receive suitable fastening bolts 10 70 which connect the two sections together and are retained in said openings by means of thumb nuts 11. In Fig. 1 the crutch is shown in a non-adjusted position by the full lines and in this position the fastening 75 bolts 10 are passed through the openings in the upper and lower ends of the legs 8 and through corresponding openings in the legs 4. However, when adjusting the sections as shown by dotted lines it is evident that 80 these fastening bolts may be passed through any of the intermediate openings formed in said legs to retain the sections in their proper adjusted position.

It is to be also understood that I have 85 shown my invention merely in its preferred embodiment and I therefore reserve the right to change the construction and arrangement of the parts as I see fit providing that any such changes contemplated come within the 90 scope of the appended claim and do not depart from the spirit of the invention.

I claim:—

A crutch including upper and lower sections slidably connected together, said lower 95 sections comprising a pair of legs extending in parallelism for a portion of their lengths, and having their lower ends directed inwardly and secured together, said upper section comprising a shoulder rest having the 100 end portions thereof engageable at times with the upper ends of said legs, a second

short pair of legs depending from said shoulder rest and disposed between the parallel portions of said first mentioned legs and corresponding in length to said parallel portions, a transverse brace connecting said first mentioned legs above the inwardly directed lower ends thereof and serving as a support for the lower ends of said short legs

and a hand grip connecting and bracing the lower end of said short leg.

In testimony whereof I affix my signature in presence of two witnesses.

ARTHUR BELL.
